FAIR LEAD OR THE LIKE

Noel J. Frisch, 506 McKinley Court, San Leandro, Calif.

Filed May 29, 1961, Ser. No. 65,387

Term of patent 14 years

(Cl. D54—11)

FIG. 7 is a fragmentary cross sectional view taken on line 7—7 of FIG. 5.

I claim:

The ornamental design for a fair lead or the like, substantially as shown.
